UNITED STATES PATENT OFFICE.

AUGUSTUS G. DAVIS, OF BALTIMORE, MARYLAND.

TELEPHONE-SWITCH.

SPECIFICATION forming part of Letters Patent No. 498,243, dated May 30, 1893.

Application filed November 25, 1892. Serial No. 452,974. (No model.)

To all whom it may concern:

Be it known that I, AUGUSTUS G. DAVIS, a citizen of the United States, residing at Baltimore, in the State of Maryland, have invented 5 certain new and useful Improvements in Telephone-Switches, of which the following is a specification.

The object of this invention is to provide a 10 depressible switch-operating part in a telephone, which part is manually depressed and as long as so held closes the main-line circuit through the receiver of the telephone, and when relieved of manual pressure is automatically returned to its normal position 15 whereby such circuit is broken.

The invention is illustrated in the accompanying drawings, in which—

Figure 1 shows a side view of a telephone provided with one form of my improvement 20 and illustrates the application of the invention. Fig. 2 shows a sectional view of the telephone-box with an edge view of the switch-parts, and a side view of the elbow-rest. Fig. 3 shows an inside view of the side of the 25 telephone-box on which the switch-parts are mounted. Fig. 4 shows a bottom view of the telephone-box with the rest-arm turned in. Fig. 5 shows a similar view to Fig. 2 of a different form of my improvement. Fig. 6 shows 30 a similar view to Fig. 3 of this latter form.

For the better carrying out of my invention I locate the transmitter, A, above the telephone-box, B, in which the dynamo, C, and switch-devices are contained, the advantage 35 of which will appear hereinafter. Within the said box, B, and attached on one side of the same is a spring contact-strip or finger, a, which forms the terminal of a conductor connected with one pole of the dynamo, C. Opposed to this spring-finger, a, is a pair of similar spring contact strips or fingers, b, which form terminals of conductors in the main line circuit through the telephone receiver, D, which is of the usual construction.

In the form shown in Figs. 2 and 3, a switch-lever, E, has one end pivoted at the front of 45 this side of the box and at this pivotal point is connected with a conductor leading from the other pole of the dynamo. This switch- 50 lever is arranged to vibrate between the contact-finger, a, and the pair of fingers, b, and

when in contact with the said finger, a, the circuit is made through the dynamo, and it is out of contact with the two fingers, b, whereby the main-line circuit through the receiver 55 is broken.

A vertically sliding rod, G, is jointed to the free end of the lever, E, and projects from the bottom of the box, B; this projecting end of the rod is round and a horizontal arm, H, 60 is swiveled on it, and may project out at one side of the box, or be turned in under the bottom of the said box for convenience in shipping, as shown in Fig. 4. A rest-piece, I, of suitable form for a person's elbow, is mounted on said horizontal arm. A spring, J, holds the arm and connecting-rod, G, up and thereby keeps the switch-lever, E, in contact with the terminal-finger, a, which is above it, and the receiver is thus cut out of the main-line 70 circuit, while the dynamo circuit is closed; in contradistinction to the usual switch in which the spring tends to cut-out the dynamo and close the circuit through the receiver, and the depression of the switch-piece reverses this 75 condition. In its normal position the rest-block, I, is above the bottom of the box, B, and to turn it in under the same, it must first be depressed. Hence the spring, J, will also serve to hold this block close against the bottom of the box when the said block is turned 80 to the position shown in Fig. 4.

It will be observed that the transmitter being above the box, and the horizontal arm, H, below the same, the said arm forms a convenient rest for the elbow while the receiver is held to the ear in the hand of the operator's arm which thus finds a resting place, and at the same time the mouth is directly in front of the transmitter. Now when the 90 elbow is rested upon the projecting arm, H, the latter is depressed and through the connecting rod, G, pulls down the switch-lever, E, into contact with the terminals, b, thus closing the main-line circuit through the receiver, and hence as long as the operator keeps his elbow resting on the arm, this circuit is maintained, while he is at the same time provided a rest for his arm which is holding the receiver. Upon removing his elbow from 95 the rest-arm,—when through using the telephone,—the spring, J, returns the parts to 100

their normal positions and thus breaks the circuit through the receiver.

The switch is operated entirely independent of the receiver and the latter when not in use may be placed wherever desired without regard to the switch.

In the construction shown in Figs. 5 and 6, the terminal, a' , of the dynamo conductor laps the terminals, b' , of the main-line circuit, 10 and a lever, E' , is pivoted within the box to an arm, E^2 , which occupies an opening or notch in the side of the box and is secured to the box by a flange-plate, e , fitting against the outside of the box. This lever, E' , has 15 an upward-extending arm, E^3 , within the box and said arm has a lateral end-portion, E^4 , which stands between the terminals, b' , and the terminal, a' . A spring, J' , connects a lug, f , on the lever with a lug, f' , on the flange-plate, e , and holds the said lateral end-portion, E^4 , in contact with the terminal, a' , thus closing the dynamo-circuit and cutting out the receiver. The lever, E' , projects laterally out of the box and is jointed by a knuckle-joint, g . The outer member, E^5 , of the lever carries an elbow-rest-piece, I' , and when not in use this rest-piece may be folded up against the side of the box as indicated in dotted lines, by turning the outer member of the lever on 30 the knuckle-joint, g . It will be apparent that the manner of use with this latter form of switch is the same as before explained of the first-described form.

It is obvious that other means might be employed to accomplish my purpose without departing from the invention.

Having thus described my invention, what I claim as new, and desire to secure by Letters Patent, is—

4c 1. The combination with the terminal of a

conductor in the main-line circuit through the receiver of a telephone; of a movable switch-piece arranged to make contact with such terminal and thereby close the circuit through the receiver; a spring holding said switch-piece out of such contact; and a vertically-movable elbow-rest connected with said movable switch-piece and so located that the elbow may rest upon it and thereby depress it to close the circuit through the receiver, while the said receiver is held to the ear by the same arm.

2. The combination with the terminal of a conductor in the main-line circuit through the receiver of a telephone, of a movable switch-piece arranged to make contact with such terminal and thereby close the circuit through the receiver; a spring holding said switch-piece out of such contact; a vertical sliding rod connected with said switch-piece; and an arm swiveled on said rod and forming a rest for the elbow of the operator while using the telephone.

3. The combination with the terminal of a conductor in the main-line circuit through the receiver of a telephone; of a movable switch-piece arranged to make contact with such terminal and thereby close the circuit through the receiver; a spring holding said switch-piece out of such contact; and a vertically-movable elbow-rest connected with said movable switch-piece and arranged to be turned to lie against the box when not in use.

In testimony whereof I affix my signature in the presence of two witnesses.

AUGUSTUS G. DAVIS.

Witnesses:

F. PARKER DAVIS,
JNO. T. MADDOX.
